UNITED STATES PATENT OFFICE

129,282

DESIGN FOR A BORDER FOR A PROTECTIVE MAT FOR KITCHEN TABLES, STOVES, AND THE LIKE

James R. Caldwell, Wooster, Ohio, assignor to The
Wooster Rubber Company, Wooster, Ohio

Application June 18, 1941, Serial No. 101,532

Term of patent 7 years

To all whom it may concern:

Be it known that I, James R. Caldwell, a citizen of the United States, residing at Wooster, in the county of Wayne and State of Ohio, have invented a new, original, and ornamental Design for a Border for a Protective Mat for Kitchen Tables, Stoves, and the Like, of which the following is a specification, reference being had to the accompanying drawing, forming part thereof, wherein:

Figure 1 is a plan view of a border for a protective mate for kitchen tables, stoves and the like embodying my new design.

Figure 2 is an enlarged fragmentary cross-sectional view showing the contour of the tubular portions of the border illustrated in Figure 1; and,

Figure 3 is an enlarged fragmentary detail view of a corner of the border illustrated in Figure 1.

I claim:

The ornamental design for a border for a protective mat for kitchen tables, stoves, and the like, substantially as shown.

JAMES R. CALDWELL.
